UNITED STATES PATENT OFFICE.

WILLIAM C. CUTLER, OF NORTH GLENDALE, CALIFORNIA.

DIRECTORY-MACHINE.

1,353,458.

Specification of Letters Patent. Patented Sept. 21, 1920.

Application filed January 9, 1920. Serial No. 350,420.

To all whom it may concern:

Be it known that I, WILLIAM C. CUTLER, a citizen of the United States, residing at North Glendale, in the county of Los Angeles and State of California, have invented a new and useful Directory-Machine, of which the following is a specification.

This invention relates to devices displaying desired information when operated.

10 One object of this invention is to provide a simple device for displaying information by simplified means.

Another object is to prevent a moving of cards before set by the setting means.

15 Another object is to provide setting means absolutely independent from the lifting means for the cards.

Another object is to prevent a throwing out of the cards from their resting and inoperative position while the card selecting or setting means are operated.

Another object is to provide such means by which the cards may be set either by push button or pulley mechanism.

25 Another object is to provide means by which the cards can be lifted out of their resting and inoperative position by lever, foot pedal, button, platform, or any other similar suitable means.

30 Other objects will appear from the following description and appended claims as well as from the accompanying drawings, in which—

Figure 1 is a perspective view of the outside of the device.

Fig. 2 is a detail fragmentary sectional front elevation of the several means supporting and operating the cards or information displaying means in normal and resting 40 position.

Fig. 3 is a detail side elevation of the setting means.

Fig. 4 is a detail fragmentary side elevation of the lifting means.

45 Fig. 5 is a detail side view of the lifting carriage seen in direction of the arrows 5—5 of Fig. 2.

Fig. 6 is a side elevation of the lifting carriage seen in the direction of the arrows 50 6—6 of Fig. 2.

Fig. 7 is a side elevation of the rest and supporting bars for the cards or displaying means.

Fig. 8 is a detail fragmentary front elevation of the setting means.

55 Fig. 9 is a slight modification of the setting means in Fig. 8.

Fig. 10 is a detail fragmentary front elevation of the lifting means for the cards and displaying means.

60

Fig. 11 is a detail fragmentary front elevation of the interlocking means between the setting means and the lifting means.

Fig. 12 illustrates a foot lever connection for the lifting means. Similar numbers refer to similar parts throughout the several views.

Fig. 13 is a detail fragmentary side elevation of the retarding means for the lifting mechanism.

70

Fig. 14 is a fragmentary end elevation of the inside mechanism of the device, the end plate of the cabinet being taken away entirely, the lifting mechanism being shown in a position having a card lifted out of resting position in contrast to the resting position of all the several parts of the device in the illustration in Fig. 2.

75

Fig. 15 is a vertical cross sectional view of the device with the inside mechanism assembled therein partly broken away to not cover other parts, one of the cards is illustrated partly lifted in engagement with the lifting mechanism, the card engaged between the prongs 38 of the small traveling and lifting member and that member engaged by the prongs 34 in the lifting bar 35.

80

In Fig. 1, 13 designates the cabinet or box or container for the displaying means and the several operating means. The front side 14 of this cabinet is provided with an opening 15 previously closed by a glass plate to allow displaying of information from the inside to the observer outside of the cabinet.

90

Slots 16 and 17 are provided at suitable places to allow operating of the device from the outside.

95

In the drawing buttons 18 and 19 are illustrated but it will be easily understood that other similar suitable means can easily be provided as long as an operating similar to this can be had.

100

A simple desk 20 is provided in front of the device to show and index and to allow for the use of the operator or information seeking party or person.

105

The button 19 is provided in connection with a cable or chain 21 for operating the setting mechanism. The cable or chain may of course be of any suitable material as long as it allows an operating of this setting mechanism. Pulleys 22 are illustrated in Fig. 3 to guide this flexible means 21, and since such flexible means naturally must be on

110

both ends of the cards 23 (see Fig. 2), as disclosed in Fig. 8, it is only natural that a common shaft 24 must be provided for two oppositely arranged pulleys so as to operate both flexible means on both ends of the cards at the same time equally.

The flexible member 21 is provided with a suitable number of prongs 25 projecting sidewise from the flexible member as is 10 illustrated in Fig. 2 and Fig. 3.

These prongs or side members 25 are engaged with corresponding prongs or members 26 on the traveling and lifting member 27.

15 The traveling and lifting member constitutes a small device having on one end a plate 28 and on the other end a plate 29 connected by pins 30.

This small traveling member can easily 20 slide back and forth crosswise to the whole device along the slot 31 in the retarding plate 32 illustrated in Fig. 13 as long as engaged by the prongs 25 and the flexible member 21. This traveling member is so 25 located during the setting operation that it freely travels in the space 33 above the prongs 34 in the member 35 illustrated in Fig. 4. The lifting mechanism naturally constitutes two such members 35 to engage 30 with two of the small traveling members as illustrated in Fig. 10.

The common shaft 36 is naturally provided to insure a common action to the two members 35 when operated by the button 18.

35 The traveling member 27 has furthermore an extension 37 provided with prongs 38 (see Figs. 2 and 6). This extension and prongs are adapted to engage with the ends 39 of the pins or engaging members of the cards 23, after having been set and when operated to be lifted out of their resting position into displaying position. These pin ends 39 of the cards 23 rest, normally in the recesses between the prongs 40 45 of the rest bar 41. (See also Fig. 7.)

This whole arrangement is made to prevent a disturbing of the cards or displaying means when in their resting position while the lifting mechanism is being set for a selection of a certain card or displaying means, the small traveling member 27 being normally so far below the pin ends 39 as not to come in contact with the prongs 38 of the traveling member while operated by the 50 inter-engaging of the prongs 25 of the flexible member with the prongs 26 of the traveling member during such setting operation.

Such disturbance of the display means is 60 furthermore prevented by the interlocking of the setting means and lifting means by the interlocking device illustrated in Fig. 11. As soon as the lifting mechanism is operated by the button 18 the locking member 65 42 is naturally pressed or moved out of the

notch 43 in the lifting bar 44, causing a moving of the bar 45 in the direction toward the setting bar 46.

The setting bar 46 is provided with corresponding notches 47 to be engaged by the 70 end 48 of the bar 45. Naturally as soon as the lifting mechanism is operated the setting mechanism is absolutely locked against any movement and only after the lifting bar has been brought back to allow the engaging 75 member 42 to engage in the notch 43, the bar 45 would naturally be automatically withdrawn by the spring 49 out of one of the notches 47 in the setting mechanism.

The bars 44 and 46 are naturally preferably arranged inside of the cabinet and suitable connection with the buttons 18 and 19 show that when the buttons 18 and 19 are operated such interlocking as described above will be procured. The setting means 85 can then naturally be operated as long as the lifting mechanisms are in such resting position with the locking means 42 in engagement with notch 43. (See Fig. 11.)

To prevent a throwing out of cards or displaying means from their engaging position during the lifting operation, a suitable retarding means is preferably provided, as illustrated in Fig. 2, the dash-pot 50 naturally only allowing the rod 51 to move at 95 such a speed as provided for by its inside over-flowing capacity.

The upper end of the bar 51 constitutes the plate 32. The slot 31 is illustrated in Fig. 13 so that the small traveling member 100 27 will be suitably retarded in any position which it obtains after being set by the flexible means 21, as will be easily understood from the illustrations in Figs. 2 and 13.

The lifting mechanism, including members 35 and the members 27 (see Figs. 4 and 10) are preferably balanced by the counter weight 52, a cable or flexible member 53 connecting the members 35 with the counter weights 52.

Suitable yokes 54 are provided for guiding the lifting means in a suitable straight-up-and-down movement (see Fig. 4).

In connection with the lifting means it will easily be understood that this can also 115 be operated by a foot pedal or platform instead of or in conjunction with the button 18. (See illustration in Fig. 12.)

The rod 55 then naturally connects with the cable 53, the several levers 56 and 57 120 being operated by the foot pedal 58, as will be easily understood.

The setting mechanism can also easily be operated by different means than by the button illustrated in the several views, as will 125 be clear from the illustration in Fig. 9, where the flexible means 21 is wound around a drum 59 operated by an indicating arm 60.

Suitable marks 61 can naturally be provided on the outside near the indicating 130

points 62, as will be clear from the illustrations in Figs. 8 and 9.

The fragmentary assembly illustration in Fig. 14 shows one card 64 lifted out of the space between the cards 63 in the rest bar 41, on which this card 64 would normally be resting at a point indicated at 65, as will easily be understood. This illustration is made with just one side board of the cabinet taken off showing the whole inside mechanism, except for the several parts being broken away at points where they would in such an illustration tend to obscure the illustration. The cards are naturally not shown in their full length. The cabinet is broken off at the top end and at the bottom, as immaterial to the illustration of the operation of the inside mechanism. A portion is broken out of the bar 51, and the lower end of the dash pot 50 is left off. The rollers or pulleys 22 are naturally mounted on the side board, taken away from the illustration, since the lifting mechanism naturally normally has its resting position between the rest plate 41 and the flexible member 21 near each of the end plates of the cabinet, as can be understood from the illustration in Fig. 2, the illustration in Fig. 14 being so to say an end elevation to the sectional front elevation in Fig. 2.

It is naturally of advantage with devices of this kind to have facilities in the main body of the device for storing a possibly largest number of cards. For this reason, the storing bars or members 41 are made to extend through the whole depth of the cabinet 13, as especially illustrated in Fig. 14, being provided with such a number of (notches) or prongs 40 that displaying cards or other similar means 23 can be stored on such members 41 closely side by side through the whole depth of the cabinet.

When in such storing position, all the operating mechanism are not only absolutely disengaged from such stored displaying means but even absolutely out of reach so that it is entirely impossible to cause any harm to the displaying means when in such stored position by touching or in some way or manner operating any of the outside or inside mechanism, as will easily be understood from the illustrations in Figs. 2, 14 and 15. In Fig. 2, all operating mechanisms are shown in their resting or inoperative positions, thereby illustrating that the engaging ends of the pins 39 of the displaying means 23 are to such an extent free above any and all the operating mechanism that either of the operating mechanism can and must be moved first quite a distance before even reaching the pins 39 making it safe that no harm can come to the pins and naturally to the displaying means as long as in their resting

and inoperative position. The setting mechanism, consisting of the flexible member 21 and the pins or projecting members 25, are in such inoperative position in engagement with the prongs 26 of the traveling and lifting members 27. There are naturally preferably two such flexible members 21, one on each end of the displaying members 23, and, naturally, there are proper supporting means for the flexible members (such as the rollers or pulleys 22). Two of the pulleys 75 are preferably connected by a shaft 24 to provide uniform action on both ends of the displaying means, as will easily be understood. In this manner, both the flexible members 21 can and are operated by one outside operating means (that is in the drawings the button 19).

The lifting mechanisms are during such setting operations locked by the pawl 42, see Figs. 11 and 15, the engaging end 42 of the pawl being during the inoperative location of the lifting mechanisms normally setting in the notch 43 of the bar 44, held there by the spring 49.

As soon as the lifting mechanisms are being operated, the end 48 of the bar 45 is naturally compelled to engage in one of the notches 47 of the bar 46. This will be described more fully later on.

The lifting mechanisms will hereafter more simply be called the lifting mechanism; to include the traveling and lifting member 27, the lifting cross bar 35, and the button 18, in general. It naturally also includes the extension bar 44 downwardly from the button 18, and eventually other minor details, as flexible members for uniform action on both ends of the displaying means and other minor details described above but immaterial for the description of the operation of the lifting mechanism.

The engaging teeth or prongs 34 of the cross bars 35 are normally also out of engaging from the traveling member 27, so that the traveling and lifting member 27 can freely pass over such prongs 34 through the slots or spaces 33 provided above the prongs 34 within the cross bars 35 when operated by the flexible members 21 with the prongs 25.

As soon as the lifting mechanism is set in motion, the pawl end 42 is first compelled out of the notch 43, since the button 18 is rigidly in engagement with the downwardly extending bar 44, as will easily be understood from the illustration in Fig. 15. Such disengaging of the pawl end 42 from the notch 43 naturally causes a corresponding movement of the bar 45 toward the bar 46 of the setting mechanism thereby compelling an engaging of the end 48 of the bar 45 with one of the notches 47 of the bar 46. The bar 46 is also rigidly in engagement with the

button 19 of the setting mechanism, as will easily be understood from the illustration in Fig. 15.

When the lifting button 18 is so moved upwardly, interlocking the bars 44 and 46 and thereby locking the movement of the setting button 19, the teeth or prongs 34 of the cross bars 35 of the lifting mechanism come naturally first into engagement with 5 the pins 30 of the lifting and traveling members 27, thereby preventing these traveling members from further sidewise traveling. A further upward movement of the button 18 then causes the prongs 26 of the 10 traveling and lifting member 27 to disengage from the prongs 25 of the flexible members 21, as will easily be understood when comparing the Fig. 2 with the Figs. 14 and 15. A still further upward movement of the 15 button 18 brings the prongs 38 of the traveling members 27 into engagement with the pin ends 39 of the displaying member 23, and by the prongs 38 of the traveling members 27 the displaying members 23 are really 20 lifted out of their resting and storing position in combination with the rest of the lifting mechanism. For this reason the traveling member 27 is generally and correctly called a traveling and lifting mechanism in 25 30 the beginning of this specification.

The cross heads 32 of the retarding means extend also over the whole width of the device, having slots 31 of a length equal to the cross or sidewise movement of the traveling members, so as to freely allow the traveling members to move to any position over the 35 whole width of the device at the same time always staying engaged with the traveling member for controlling the up and down movements of the traveling members, as will 40 easily be understood from the above.

Only after such displaying member as has been lifted out of its resting and storing position on the rest bars or storing bars 41 45 has been allowed to come back into such storing position, the setting mechanism may and can again be operated as described above, as will easily be understood from the foregoing description.

50 Having thus described my invention, I claim:

1. In a directory device of the class described, a series of cards, setting means, a traveling member normally engaging the 55 setting means, the traveling member having engaging means to engage with the cards when lifted.

2. In a directory device of the class described in combination with setting and lifting means, a traveling member having means to normally engage with the setting means and adapted to be lifted by the lifting means free from setting means.

3. In a directory device of the class described, in combination with information

displaying means and setting and lifting means, a traveling member having means normally engaging with the setting means free from engagement with the lifting means as well as free from engagement with 70 the information displaying means and adapted to be engaged with the information displaying means by the lifting means.

4. In a directory device of the class described, a series of displaying members, setting means, lifting means, rest members normally supporting the displaying members in certain positions, and a traveling member having means normally engaging with the setting means and having other means 75 80 to engage with the displaying means when so operated by the lifting means.

5. In a directory device of the class described, a series of cards, rest members having means normally holding the cards in 85 certain positions, setting means having means by which to come into selective position in relation to one of the cards, and lifting means having means to bring the card in which relation the setting means 90 have been set into displaying position.

6. In a directory device of the class described, a series of cards, setting means, lifting means, a traveling member normally engaging with the setting means having 95 means adapted to be lifted from such position to engage with one of the cards, and retarding means arranged in suitable relation to the lifting means for controlling a movement of the traveling member while 100 being lifted from the setting means in engagement with the selected card.

7. In a directory device of the class described, a series of cards, indicating means on the outside of the device, traveling means, 105 means in operative connection with the indicating means and the traveling means to move the traveling means into selective position in relation to one of the cards, and lifting means to move the traveling member 110 with the selected card into displaying position.

8. In a directory device of the class described, a series of cards, setting means, lifting means, traveling members having means 115 normally engaging with the setting means and having means adapted to be lifted from the setting means when set in a selective position in relation to one of the cards, and locking means for locking the setting means 120 when the lifting means is operated and having means to lock the lifted means when the setting means is operated.

In testimony that I claim the foregoing as my invention I have signed my name in 125 the presence of two subscribing witnesses.

WILLIAM C. CUTLER.
